Letter Patent No. 9987-Dated July 16th 1874.

Design for the Plates of a Back's Stove.

The schedule referred to in these Letters Patent and making part of the same.

Be it known that I, Isaac Pfeuchte, of the City and County of St. Louis, and State of Missouri, have invented or produced a new and original Design for the Plates of a Premium Backing Stove; and I do hereby declare that the following is a full and exact description of the same, reference being had to the accompanying drawings, and to the letters of reference marked theron, making a part of this specification, in which, Fig. 1 represents the front plate, ornamented with the interlacing letters B. B. G. C. at A, and the same reversed at B as shown. Fig. 2 represents the back plate, having the band and bead ornament C, which is shown enlarged in Fig. 3. Fig. 4 represents the ornament on the front doors and on the fire door. Fig. 5 represents the oven doors, having the band and bead ornament D as shown.

Having thus described my design for the Plates of a Premium Backing Stove, what I claim as new therein and desire to secure by Letters Patent is—

The ornamental configuration and Design for the Plates of a Premium Backing Stove as herein described and shown in the accompanying drawings.
